CLAIM

The ornamental design for a square container with fixed ball, as shown and described.

DESCRIPTION

FIG. 1 is a front, side perspective view of my square container with fixed ball.

FIG. 2 is a top plan view thereof.

FIG. 3 is a bottom plan view thereof.

FIG. 4 is a side elevation view thereof, the other side being a mirror image; and,

FIG. 5 is a side elevation cross-section view thereof taken along line 5-5 of FIG. 2.
